HORACE L. ROBERTS, OF MOUNT VERNON, NEW YORK.

SHOE-POLISHING DEVICE.

Application filed July 7, 1927. Serial No. 204,029.

The object of my invention is to produce a foot operated shoe polishing device in which the operator, by moving a treadle with his foot, will cause a polishing element to pass 5 rapidly back and forth across the shoe to polish the same.

A further object is to provide a device of the above character which will be durable, compact, easy to operate, inexpensive to make 10 and composed of few parts.

My invention comprises generally, a treadle and a polishing element operated thereby, which polishing element may be made removable and which is preferably yieldingly 15 mounted, spring means being provided for yieldingly holding the treadle and the polishing element in their normal positions.

A practical embodiment of my invention is represented in the accompanying drawings, 20 in which

Fig. 1 represents the shoe polishing device in top plan, the polishing element being shown in full lines in its normal position at one side of the treadle and in dotted lines at 25 the limit of its transverse movement at the other side of the treadle and also in an intermediate position.

Fig. 2 represents a side view of the device with the parts in their normal positions.

Fig. 3 represents a similar view with the parts in the positions they assume when the treadle is depressed.

Fig. 4 represents a rear end view of the device.

Fig. 5 represents an enlarged detail section showing the spiral slot and pin connection between the treadle operated rock shaft which carries the polishing element and its turning block.

The base of the device is denoted by 1, which base may be provided with three suitable legs 2, 2, 2, serving to hold the base firmly on its support in an upwardly and forwardly inclined position. The treadle 3 may 40 be pivoted at its front end to the front end of the base by providing the base with two up- 45 rising ears 4, 4 and the treadle with a depend- 50 ing lug 5 through which ears and lug a pivot 55 pin 6 is passed.

The rear end of the treadle is yieldingly 60 supported by and spaced above the rear end of the base, in the present instance by pro- 65 viding a link comprising upwardly and for- 70 wardly inclined arms 7, 7, pivoted at their 75 lower ends to the base by the pivot pin 8. The upper ends of these arms carry a pair of

inwardly projecting pins 9, 9, on which are 60 mounted rollers 10, 10 exterior to the arms 7, 7. A shaft turning block 11 is mounted on the pins 9, 9 between the arms 7, 7. A longitudinally disposed treadle operated rock 65 shaft 12 passes through the depending lug 5 of the treadle and the turning block 11, the rear end of which shaft is provided with a spiral groove 13 within which the inner ends 65 of the pins 9, 9 are located. This rock shaft 12 is provided with a collar 14 which engages the inner face of the depending lug 5 of the treadle.

Beyond the front end of the treadle a resilient arm is adjustably fastened to the rock shaft 12, in the present instance by means of a set screw 15 passing through the hub 16 of the arm into engagement with the said shaft. The resilient arm is herein shown as 70 a closely coiled spring 17, the outer end of which is provided with a head 18 having lateral ears 19, 19 from which long pins 20, 20 project rearwardly. The polishing element is shown as a tubular pad 21 of any material 75 suitable for polishing such, for instance, as wool, which pad is removably carried by the pins 20, 20 by inserting the pins into the bore 80 of said tubular pad.

The treadle 3 and the polishing element are 85 yieldingly held in their normal positions with the polishing element at one side of the treadle by spring means which, in the present instance, comprises a coil spring 22 surrounding the rock shaft 12 and located between a collar 90 23, fixed on said shaft and a tubular extension 24 of the shaft turning block 11. A lug 25 depending from the treadle 3 engages the rear 95 face of the shaft turning block 11 when the parts are in their normal position for limiting the movements of the treadle and polishing element. A yielding pad 26 is provided 100 on the base 1 in position to receive the impact of the turning block 11 when the treadle is depressed.

When it is desired to polish the shoe, the foot is placed upon the treadle and the treadle is depressed. The downward movement of the inclined arms 7 will cause the rollers 10 to travel along the underside of the treadle 3, carrying therewith the shaft turning block 11, with the pins 9 naturally moving along within the spiral groove 13 and thereby rocking the shaft 12. Upon releasing the pressure upon the treadle the spring 22 returns 105 the elements to their normal position, again 110 rocking the shaft but in the reverse direction.

The device thus is operated to cause the polishing element to pass rapidly back and forth across the shoe in yielding contact therewith. This yielding contact is obtained by 5 the resilient arm 17 which carries the polishing element.

From the above description it will be seen that I have provided a very simple shoe 10 polishing device and one in which the polishing element is not only caused to yieldingly engage the shoe as it passes back and forth across the same, but is also capable of being removed and replaced at any time.

Furthermore, it will be seen that the device 15 may be easily operated as the rear end of the treadle rests upon the anti-friction rollers 10, 10 carried by the link 7, 7.

It is evident that various changes may be 20 resorted to in the construction, form and arrangement of the several parts without departing from the spirit and scope of my invention; hence, I do not wish to be limited to the particular embodiment herein shown and described, but what I claim is:—

25 1. In a shoe polishing device, a base, a shoe supporting treadle pivoted thereon, a shaft disposed longitudinally with respect to the treadle, a resilient arm fast on said shaft, a polishing element carried by said arm, and means operated by the movement of the treadle for rocking said shaft to move the polishing element laterally across the shoe of the operator on the treadle.

30 2. In a shoe polishing device, a base, a shoe supporting treadle pivoted thereon, a shaft disposed longitudinally with respect to the treadle, a closely coiled spring arm fast on said shaft, a polishing element carried by said arm, and means operated by the movement of the treadle for rocking said shaft to move the polishing element laterally across the shoe of the operator on the treadle.

35 3. In a shoe polishing device, a base, a shoe supporting treadle pivoted at its front end thereon, a shaft disposed longitudinally with respect to the treadle, a resilient arm fast on said shaft beyond the front end of the treadle and having rearwardly projecting pins, a tubular polishing element removably carried by said pins, and means operated by the movement of the treadle for rocking said shaft to move the polishing element laterally across the shoe of the operator on the treadle.

40 4. In a shoe polishing device, a base, a shoe supporting treadle pivoted at its front end thereon, a shaft disposed longitudinally

with respect to the treadle, a closely coiled spring arm fast on said shaft beyond the front end of the treadle and having rearwardly projecting pins, a tubular polishing element removably carried by said pins, and means operated by the movement of the treadle for rocking said shaft to move the polishing element laterally across the shoe 65 of the operator on the treadle.

5. In a shoe polishing device, a base, a shoe supporting treadle pivoted thereon, a shaft disposed longitudinally with respect to the treadle, a closely coiled spring arm fast on 70 said shaft, a polishing element carried by said arm, and means operated by the movement of the treadle for rocking said shaft to move the polishing element laterally across the shoe of the operator on the treadle.

6. In a shoe polishing device, a base, a treadle pivoted at its front end to the base, an inclined link pivoted at its lower end to the rear end of the base, rollers and a block carried by the link at its upper end, on which rollers the rear end of the treadle rests, a longitudinally disposed shaft passing through the block and rotatively mounted at the front end of the treadle, a resilient arm fast on said shaft, a polishing element carried by said arm, said longitudinal shaft having a spiral groove in its rear end and said block having a pin engaging said spiral groove whereby the vertical movement of the treadle will rock the shaft to move the polishing element laterally 80 across the shoe of the operator on said treadle.

7. In a shoe polishing device, a base, a treadle pivoted at its front end to the base, an inclined link pivoted at its lower end to the rear end of the base, rollers and a block carried by the link at its upper end, on which rollers the rear end of the treadle rests, a longitudinally disposed shaft passing through the block and rotatively mounted at the front end of the treadle, a resilient arm fast on said shaft, a polishing element carried by said arm, said longitudinal shaft having a spiral groove in its rear end and said block having a pin engaging said spiral groove whereby the vertical movement of the treadle will rock the shaft to move the polishing element laterally across the shoe of the operator on said treadle, and spring means for holding the treadle and polishing element in their normal positions.

In testimony, that I claim the foregoing as my invention, I have signed my name this 6th day of July, 1927.

HORACE L. ROBERTS.
